UNITED STATES PATENT OFFICE.

CHARLES W. MCWANE, OF LYNCHBURG, VIRGINIA, ASSIGNOR OF ONE-HALF
TO HENRY E. MCWANE, OF LYNCHBURG, VIRGINIA.

COLLAPSIBLE CORE-BARREL.

SPECIFICATION forming part of Letters Patent No. 740,772, dated October 6, 1903.

Application filed October 31, 1902. Serial No. 129,614. (No model.)

To all whom it may concern:

Be it known that I, CHARLES W. MCWANE, a citizen of the United States, residing at Lynchburg, in the county of Campbell and 5 State of Virginia, have invented a new and useful Collapsible Core-Barrel, of which the following is a specification.

This invention relates more particularly to that class of core-barrels employed in the 10 manufacture of cast-iron pipes.

One aim of the invention is to provide a structure which will obviate to a great extent the use of hay rope now ordinarily employed by being wrapped around a barrel 15 core or pipe and usually protected by a double coating of heat-resisting material.

More particularly it is the object to provide a structure which is made up of a few simple parts that may be readily associated and are 20 not easily deranged, though said structure can be dismembered with facility, so that any element can be repaired and renewed, the whole constituting a barrel which will form 25 a stable core during the casting operation and will automatically collapse in order that it may be removed without difficulty.

Two forms of the invention are illustrated in the accompanying drawings; but it will be apparent from an inspection of the claims 30 that the structures herein illustrated are open to changes and modifications.

In said drawings, Figure 1 is a side elevation of the improved barrel, an intermediate portion thereof being broken away. Fig. 2 35 is a longitudinal sectional view through the same. Fig. 3 is a transverse sectional view. Fig. 4 is a detail view of a portion of the stem, showing one of the keyhole-slots. Fig. 5 is a side elevation of a modified form of construction. Fig. 6 is a longitudinal sectional view 40 through the same. Fig. 7 is a transverse sectional view taken on the line $x-x$ of Fig. 6. Fig. 8 is a longitudinal sectional view taken on the line $y-y$ of Fig. 6.

Similar numerals of reference denote corresponding parts in all the figures of the drawings.

In the embodiment shown in the first four figures a stem 10 is employed, which is tubular in form, being provided with a longitudinal bore 11. This stem is provided with an-

nular series of keyhole-slots 12, the contracted portions 13 of which are disposed below the enlarged portions. A plurality of independent staves 14 surround the stem 10 and 55 are movable toward and from the same, these staves carrying inwardly-projecting studs 15, which are riveted, as shown at 16, to the staves and have on their inner ends enlarged heads 17. The studs slidably engage in the keyhole-slots 12, the enlarged portions of which are of sufficient size to permit the passage of the heads, while the contracted portions 13, though receiving the shanks of the studs, will not permit the withdrawal of the heads. The 60 staves are held against longitudinal movements upon the stem 10 by means of collars 18, secured upon the stem and abutting against said staves. The staves are provided with the usual vent-openings, as 19. The staves, 70 while held against their longitudinal movements in the manner above described, are freely movable toward and from the stem 10, and when in their projected positions their adjacent edges are spaced apart, constituting 75 shoulders 20. Between these shoulders is packed combustible material 21, which is in the form of hay rope, excelsior, or the like. This material, as will be observed by reference to Fig. 3, filling the spaces between the 80 edges, normally holds the staves in their projected positions.

The manner of using this structure will be obvious. After the staves have been secured in the manner shown in Fig. 3 a coating of 85 clay or other suitable material (indicated at 22) is placed about the core-barrel. When the casting is made, the heat from the molten metal passing through the protective coating 22 will destroy the holding means 21, and as 90 a result the barrel can collapse, or, in other words, the staves can move freely in toward the stem, whereupon the barrel can be withdrawn without difficulty from the casting.

In view of the fact that it requires considerable time to properly pack the material between the spaced edges of the staves in the manner shown in Fig. 3 the modified construction illustrated in Figs. 5, 6, 7, and 8 is believed to be advantageous. The same idea 100 is still involved, however, for it will be seen that the same stem and staves are employed,

including their connections. The adjacent edges of said staves form the shoulders 20, against which the combustible material bears, the same as above described; but in this 5 stance said shoulders are covered by flanges 23, one of which is secured to one edge of each stave and overlaps the adjacent edge of the adjoining stave. These flanges are provided at suitable intervals with openings 24, 10 arranged to aline with the spaces between the edges of the staves when the staves are in their projected positions. The stem 10 is likewise provided with openings 25, which are also alined with the spaces. Through the 15 openings 24 are passed wooden or other combustible wedges 26, which thus are forced between the spaced edges of the staves and constitute the holding means for maintaining them in projected positions, as will be readily 20 understood. The action of this structure is exactly the same as the other, and it will be evident that it may be prepared with much greater speed and less care.

The advantages for this construction may 25 be summed up as follows: In the first place it does away with the necessity for great quantities of rope now generally employed, which must be protected by thick coatings of heat-resisting material. Furthermore, it is entirely practicable, for the reason that the parts 30 are few, simple, and not liable to injury from the great heat to which they are necessarily subjected. At the same time should it become necessary to remove any or all of the 35 staves by withdrawing one of the collars said staves may be moved longitudinally, thereby bringing the heads of the studs into alinement with the enlarged portions of the key-hole-slots, whereupon the staves may be detached.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 50 of the invention.

Having thus described my invention, what I claim as new, and desire to secure by Letters Patent, is—

1. In a collapsible core-barrel, the combination with a tubular stem, of separate staves located outside the stem and movable toward and from the same, connections between the stem and each stave, said connections extending through the walls of and being movable 55 into the stem, said staves having shoulders at their opposite sides that are spaced apart when the staves are projected to permit combustible means being arranged between and in engagement with the shoulders to hold said 60 staves in their projected positions.

2. In a collapsible core-barrel, the combination with a tubular stem, of separate staves

surrounding the stem and movable toward and from the same, studs riveted to the staves and slidably extending into the stem, said 70 studs having heads at their inner ends which are arranged to engage the stem to limit the outward movements of the staves, said staves having shoulders at their sides which, when the staves are in their outermost position, are 75 spaced apart to permit combustible holding means being arranged between and in engagement with the shoulders to hold said staves in their projected positions.

3. In a collapsible core-barrel, the combination with a supporting-stem, of staves movable toward and from the same, and studs secured to the staves and engaging the same, said 80 studs having transverse and longitudinal movements with relation to the stem and being 85 detachable from the stem upon said longitudinal movements.

4. In a collapsible core-barrel, the combination with a tubular supporting-stem having keyhole-slots in its walls, of staves movable 90 toward and from the stem, and headed studs carried by the staves and engaging in the key-hole-slots.

5. In a collapsible core-barrel, the combination with a supporting-stem, of staves movable toward and from the stem, studs secured to the staves and engaging the same, said 95 studs and staves having transverse and longitudinal movements with relation to the stem, the studs being detachable from the stem upon their longitudinal movements, and means for securing the staves and studs against said longitudinal movements.

6. In a collapsible core-barrel, the combination with a tubular supporting-stem having keyhole-slots, of staves movable toward and from the stem, headed studs carried by the staves and engaging in the keyhole-slots, and collars secured to the stem at the ends of the staves to prevent the longitudinal movement 105 of the latter.

7. In a collapsible core-barrel, the combination with a supporting - stem, of staves loosely attached to the supporting-stem and movable toward and from the same, said staves 115 when in their projected positions having spaces between their adjacent side edges, and flanges carried by certain staves and overlapping the adjacent edges of those next adjoining, said flanges having openings that 120 aline with the spaces between the edges of the staves.

8. In a collapsible core-barrel, the combination with a supporting - stem, of staves loosely attached to the supporting-stem and 125 movable toward and from the same, said staves when in their projected positions having spaces between their adjacent side edges, flanges carried by certain staves and overlapping the adjacent edges of those next adjoining, said flanges having openings that 130 aline with the spaces between the edges of the staves, and combustible wedges passing through the openings and engaging the edges

of the staves to hold said staves in their projected positions.

9. In a collapsible core-barrel, the combination with a supporting - stem, of staves 5 loosely attached to the supporting-stem and movable toward and from the same, said staves when in their projected positions having spaces between their adjacent side edges, and a flange carried by each stave and overlapping the adjacent edge of the adjoining stave, said flanges and stem having alined openings 10 that also aline with the spaces between the edges of the staves.

10. In a collapsible core-barrel, the combination with a supporting-stem, of staves mov- 15

able toward and from the same, studs secured to the staves and engaging the stem, said studs having transverse and longitudinal movements with relation to the stem and being detachable from the stem upon said longitudinal movements, and means for preventing the longitudinal movements of the staves and studs. 20

In testimony that I claim the foregoing as my own I have hereto affixed my signature in 25 the presence of two witnesses.
